UNITED STATES PATENT OFFICE.

JULIUS W. LANDQUIST, OF WOODLAND, CALIFORNIA.

AX-WEDGE.

1,362,945.

Specification of Letters Patent. Patented Dec. 21, 1920.

Application filed July 26, 1918. Serial No. 246,926.

To all whom it may concern:

Be it known that I, JULIUS W. LANDQUIST, a citizen of the United States, residing at Woodland, in the county of Yolo and State of California, have invented certain new and useful Improvements in Ax-Wedges, of which the following is a specification.

This invention relates to wedges for holding the heads of tools upon the handles thereof and has for its object the production of a simple and efficient wedge which may be very easily inserted through the outer end of the tool handle.

Another object of this invention is the production of a simple and efficient wedge which will firmly engage the tool head and also firmly bite into the handle of the tool for preventing the tool head from becoming accidentally detached from the handle.

With these and other objects in view this invention consists of certain novel constructions, combinations and arrangements of parts as will be hereinafter fully described and claimed.

In the drawings:—

Figure 1 is a side elevation partly in section of a tool head secured upon the handle by means of the improved wedge,

Fig. 2 is an end view of a tool head mounted upon a tool handle,

Fig. 3 is a sectional view of a portion of a tool head and handle, showing the wedge about to be inserted in position.

By referring to the drawings, it will be seen that 1 designates the handle of the tool upon which is mounted a head 2. The head 2 is provided with a tapering notch 3 formed upon the inner edge of the handle receiving aperture 4 and this notch 3 is substantially square in cross section for the purpose of receiving the upwardly inclined rib portion 5 of the wedge 6, it being noted that the top edge of the aperture 4 and the notch 3 conform to the shape of the wedge 6. The wedge 6 is provided with a straight side edge 7 which terminates at its outer end in the upwardly inclined rib 5 and the opposite edge 8 of the wedge is curved and merges into the straight edge 7 at the inner end of the wedge for producing a tapering point. The wedge 6 is provided with a flat or straight outer end 9 for the purpose of facilitating the insertion of the wedge 6 into the handle 1. It should be understood, as shown in Fig. 1, that the rib 5 of the

wedge 6 has a straight edge 5' which is inclined downwardly toward the straight edge 7, thus forming an angular portion at their point of junction, and the notch 3 is so formed as to conform to the shape or inclined edge 5' of the rib 5.

It of course should be understood that the wedge 6 is preferably formed of metal and may be used for securing the head of any suitable tool in engagement with a supporting handle.

Although there is illustrated an ax head secured to the handle 1, a hammer or other suitable tool head may be secured to the handle by means of the improved wedge.

When inserting the wedge 6 in the end of the handle 1, the wedge travels between the lines A—B and C—D indicated in Fig. 1, until it has reached the point indicated by the dotted line structure, a distance about one half the length of the straight edge 7, at which time, the ribbed portion 5 of the wedge is brought into contact with the tapering notch 3 so that as the wedge is driven farther into the handle, the entrance of the rib 5 into the notch causes the point of the wedge to penetrate in a forwardly and upward direction, while the lower edge of the rib is forced downwardly into the outer end of the handle, in proportion to the upward travel of the penetrating point; the arcuate edge 8 tending to swing the entire wedge in an arc below the point 4 of Fig. 1, the innermost edge of the notch 3 constituting the fulcrum point. As the wedge is driven farther in between the ax head and the handle, the pointed penetrating edge 7 tends to bite into and separate the fibers of the handle portion lodged thereabove permitting the edge 7 to be brought into position against the wall 4 during the gradual and continual crowding of the outer end of the handle, indicated at 10 in Fig. 1, this crowding being effected by the curved lower edge 8 as the rib is forced into the notch. The wedge, therefore, cuts its own path way through the handle for locking the wedge 6 in the wooden handle 1 and preventing the same from moving or creeping outwardly. It will thus be seen that the wedge practically bruises its way into the handle so as to compress and separate the fibers in a manner causing them to react against the wedge and by reason of their adhesion thereto to cause the same to be more firmly embedded therein. The

notch 3 not only acts as a guide for holding the wedge 6 to a true course, but also constitutes an inclined plane which determines the angle at which the wedge is started into 5 the handle 1.

The engagement between the handle and the wedge will cause the wedge to be continually held in a binding or jammed engagement with the head 2 within the notch 10 and the aperture, thus holding the device assembled.

What is claimed is:—

In a device of the character described, the combination of a head having an inclined 15 notch extending thereinto from one side edge and a handle receiving aperture extending thereinto from its opposite side edge, said notch and aperture communicating with each other, a handle inserted into 20 said aperture, and a wedge formed from a single piece of material comprising an elongated substantially flat structure, said wedge having one edge thereof curved in the arc of a circle throughout the entire 25 length of the wedge, the opposite edge of

said wedge having a straight portion from which extends an inclined edge at an oblique angle, thus forming an angle at the junction of the straight edges, and said wedge having a pointed inner end and a 30 flat outer end, thus permitting the same to be driven into said handle and to fit within said notch and said aperture, the straight edges of said wedge conforming to the shape of the top of the aperture and said notch, 35 whereby the wedge will crowd the handle directly therebeneath, although the handle upon each side portion of the wedge will be left intact, thus causing the wedge to be firmly held by the handle and to be jammed 40 in a binding engagement with the head, whereby the head will be firmly held upon said handle.

In testimony whereof I affix my signature in presence of two witnesses.

JULIUS W. LANDQUIST.
